HENRY KAGY, OF PHILADELPHIA, PENNSYLVANIA, ASSIGNOR TO THOMAS POTTER, SON & COMPANY.

Design No. 4,691, dated February 28, 1871.

DESIGN FOR AN OIL-CLOTH PATTERN.

The Schedule referred to in these Letters Patent and making part of the same.

To all whom it may concern:

Be it known that I, HENRY KAGY, of the city and county of Philadelphia, in the State of Pennsylvania, have invented and produced a new and original Design for an Oil-Cloth, of which the following is a specification.

My design is represented in the accompanying photographic illustration, which forms a part of this specification.

What I claim as new, and desire to secure by Letters Patent of the United States, is—
The design for an oil-cloth, as shown.

HENRY KAGY.
